TUBING SHOE VALVE

William W. Lloyd, Beggs, Okla.

Application May 2, 1935, Serial No. 19,521

5 Claims. (Cl. 103—220)

This invention relates to a tubing shoe valve particularly adapted for coaction with plunger pumps.

It is particularly aimed to provide a structure which operates by the action of the fluid and a construction wherein sand, mud, pieces of cups and the like, are trapped, and washed out or removed by downward flow of the fluid.

The more specific objects and advantages will become apparent from a consideration of the description following taken in connection with accompanying drawings illustrating an operative embodiment.

In said drawings:—

15 Figure 1 is a central longitudinal section through the device;

20 Figures 2 and 2^a are enlarged central longitudinal sectional views taken through the upper portion and lower portions of the device, respectively, taken on the plane of lines 2—2 and 2—2^a—25 of Figure 1;

25 Figure 3 is a view similar to Figure 1 but showing the working valve in open position as contrasted with the closed position of Figures 1 and 2;

Figure 4 is a cross section taken on the plane of line 4—4 of Figure 2, and

30 Figure 5 is a cross section taken on the plane of line 5—5 of Figure 2.

35 Referring specifically to the drawings, 10 designates well tubing through which a conventional sucker rod 11 operates and which carries the movable cylinder or barrel 11—a of an inverted plunger pump or working valve assembly.

The normally stationary piston of the plunger pump is shown at 12 located within said cylinder 11—a and carried by a depending tubular rod 12—a. Rod 12—a carries a piston 12—b includ-

40 ing a cage 12—c and an upwardly operating valve 12—d. Said cage 12—c is equipped with an outwardly extending flange 13. Said cylinder 12—a has the usual upwardly opening valve 12—e adjacent the top. A flange 11—b at the

45 lower end of the barrel 11—a is engageable with the piston 12 to unseat the latter through abnormal lift of the sucker rod 11 and barrel 11—a.

Screw-threaded to the lower end of the tubing 10 at 14 is a neck or nipple 15. A shell is shown 50 in sections 16 and 17, detachably screw-threaded at 18 and 19, to a shoe valve or coupling 20, shell section 17 being detachably screw-threaded at 21 to the neck 15. Concentrically of the neck 20 and screwed thereto at 21, is a pump shoe 22 which extends down into the shell 16, having

outlet ports or openings 23 therein adjacent the lower end.

Detachable or integral with the neck 20 is an upward extension 24 which has a seat 25 engageable by flange or valve portion 13, when the device is in closed position. It is obvious that I may make the part 24 detachable, if desired, in order that valve seats of different sizes may be used when desired, or worn valve seats replaced. Detachably screwed to the projection or extension 24 as at 26 is a shield 27, which terminates short of the nipple 15, in order that sand, mud, and the like, may collect between the shell portion 17 and the shield 27. A plurality of passages or ports 28, are provided through the extension 15 24 so that sand, mud and the like caught between the shield 27 and shell 17, may pass into the pump shoe 22. Section 16 of the shell, above the lower end of shoe 22, is preferably provided with any desired number of slits 29 for seepage. 20

The lower end of the pump shoe 22 has a plate 30 screw-threaded thereto as at 31, and the plate has depending spaced apart projections 32. Slightly below the plate 30, ports 33, of any desired number, are provided through the shell 25 section 16, adapted to be covered at times by a bobber 34 which is a solid or enclosed metal body, and which is urged upwardly by an expansive coil spring 35 surrounding a depending stem 36 thereon, and abutting the bobber, and 30 the lower wall 37 of the shell section 16, which lower wall is perforated as at 38, to enable fluid to enter the section 16 below the bobber 34 to act as a cushion, in combination with the spring 35 to the downward movement of such bobber. 35

The device is shown in closed position in Figure 1 in which the plunger pump barrel 11—a and piston 12 operate in the usual manner to pump fluid from a well. Abnormal elevation of the sucker rod 11 and barrel 11—a, at any desired time, will cause flange 11—b to engage piston 12 and elevate or unseat flange 13, to the open position of Figure 3. The device operates through the action of the fluid. When the plunger pump valve 12 is thus unseated at 13, 45 the bobber 34 is pushed down by the fluid, whereby the holes or ports 33 are exposed. The fluid rushes down the tubing between the shield 27 and shell section 17, and down through shield 27 working out matter collected therein. Shield 50 27 confines trash such as pieces of cups which may at times be pulled off of piston 12—b, in a direct line descending fluid, so that it cannot lodge or catch in corners or on projections; and the shield also confines sand, mud and grit be- 55

tween the same and the shell section 17, the water washing out the latter through passages 28 down shoe 22, some of the material escaping through the openings or ports 23 into shell section 16 and then through the slits 29, before the pressure is sufficient to depress the bobber 34 into the position of Figure 3, in which latter position the mud, sand and grit as well as trash is passed out through the bottom of shoe 22 and ports 33. When the pressure of the fluid subsides, the bobber 34 is returned to the position shown in Figures 1 and 2, keeping all material out with the exception of oil and some gas. It will be understood of course that the fit of the bobber 34 within the shell section 16 is somewhat loose so as to avoid any danger of binding.

The construction enables acid to be poured therethrough when the piston 12—b is unseated, the acid serving to dissolve the substances which coats the inside of the well tubing and other parts.

Various changes may be resorted to provided they fall within the spirit and scope of the invention.

25 I claim as my invention:—

1. A device of the class described having a shell member, a neck at the base thereof, a pump shoe depending from said neck, a shield in the shell member rising from the neck, a pumping device operable within the shield having means operable through abnormal movement of a part of the pumping device to open and close the pump shoe, and means of communication between the pump shoe and the space between the shield and shell member, said space serving as a trap for the collection of sand, mud and the like.

30 2. A device of the class described having a shell member, a neck at the base thereof, a pump shoe depending from said neck, a shield in the shell member rising from the neck, a pumping device operable within the shield having means operable through abnormal movement of a part of the pumping device to open and close the pump shoe, means of communication between the pump shoe and the space between the shield and shell member, said space serving as a trap for the collection of sand, mud and the like, a neck at the upper end of the shell member, tubing suspending the neck, and a sucker rod extending 35 through the tubing and connected to the pumping device.

40 3. A device of the class described having a shell member, a neck at the base thereof, a pump shoe depending from said neck, a shield in the shell member rising from the neck, a pumping device operable within the shield having means operable through abnormal movement of a part of

of the pumping device to open and close the pump shoe, means of communication between the pump shoe and the space between the shield and shell member, said space serving as a trap for the collection of sand, mud and the like, a shell member depending from said neck having ports through its wall, and a bobber in the last mentioned shell member controlling said ports according to the pressure within the device. 5

4. A device of the class described having a shell member, a neck at the base thereof, a pump shoe depending from said neck, a shield in the shell member rising from the neck, a pumping device operable within the shield having means operable through abnormal movement of a part of the pumping device to open and close the pump shoe, means of communication between the pump shoe and the space between the shield and shell member, said space serving as a trap for the collection of sand, mud and the like, a shell member depending from said neck having ports through its wall, a bobber in the last mentioned shell member controlling said ports according to the pressure within the device, the second mentioned shell member being slotted for seepage, 20 a plate on the lower end of said pump barrel, said pump barrel being perforated above the plate, said plate constituting an abutment for upward movement of the bobber, and means preventing closing engagement of the bobber with the pump barrel. 25

5. A device of the class described having a shell member, a neck at the base thereof, a pump shoe depending from said neck, a shield in the shell member rising from the neck, a pumping device operable within the shield having means operable through abnormal movement of a part of the pumping device to open and close the pump shoe, means of communication between the pump shoe and the space between the shield and shell member, said space serving as a trap for the collection of sand, mud and the like, a shell member depending from said neck having ports through its wall, a bobber in the last mentioned shell member controlling said ports according to the pressure within the device, the second mentioned shell member being slotted for seepage, a plate on the lower end of said pump barrel, said pump barrel being perforated above the plate, said plate constituting an abutment for upward movement of the bobber, means preventing closing engagement of the bobber with the pump barrel, the second mentioned shell section having a bottom perforated wall, and an expansive spring 40 within the second mentioned shell section engaging said wall and said bobber. 45
